UNITED STATES PATENT OFFICE.

BRUNO V. NORDBERG, OF MILWAUKEE, WISCONSIN, ASSIGNOR TO THE
BRUNO NORDBERG COMPANY, OF SAME PLACE.

FEED-WATER HEATER.

SPECIFICATION forming part of Letters Patent No. 542,004, dated July 2, 1895.

Application filed August 23, 1892. Serial No. 443,889. (No model.)

To all whom it may concern:

Be it known that I, BRUNO V. NORDBERG, of Milwaukee, in the county of Milwaukee and State of Wisconsin, have invented certain new and useful Improvements in Feed-Water Heaters; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The main objects of my invention are to provide for easy access to the interior of the heater and of the upper and lower tube-heads for the purpose of inspection, repairs, and removal of impurities without disturbing the connections of the heater; to counteract the lifting tendency of the steam on the upper head, and thus prevent straining and loosening the joints between the tubes and the heads in which they are secured at the ends; to prevent back-pressure through the exhaust or steam inlet; to distribute the steam among the water-tubes, and thereby utilize to the greatest possible extent the heat contained in the steam for raising the temperature of the water; to separate impurities from the water entering the heater and to facilitate their removal therefrom.

It consists of certain novel features in the construction and arrangement of parts hereinafter particularly described, and pointed out in the claims.

In the accompanying drawings like letters designate the same parts in the several figures. Figure 1 is a vertical medial section of my improved heater. Fig. 2 is a side elevation 40 of the same, a section thereof being removed and a portion of the jacket or shell being broken away at its upper end. Fig. 3 is a vertical medial section of the base of the heater, taken in a plane at right angles to that of Fig. 45 1. Fig. 4 is a horizontal cross-section of the base on the line 4 4, Fig. 2; and Fig. 5 is a similar section on the line 5 5, Fig. 2.

A is the lower tube-head and chamber, which is formed with an annular belt or space 50 a' around its sides and with a removable bottom a and constitutes therewith the base of

the heater. The outer walls of the annular steam belt or space a' are formed on opposite sides with inlet and outlet exhaust or steam openings and pipe connections a² and a³. 55

B is the upper tube-head and chamber, which is formed with a removable cover b and connected by tubes C C and a larger central tube D (which are preferably made of brass or copper or some other good conductor 60 of heat) with the lower head A. Return and outlet pipe E, passing centrally through the tube D, is secured at its lower end by a nut e to the bottom a of the lower chamber A and at its upper end by a nut e' to the upper tube- 65 head. The upper end of said pipe E is elevated and held above the bottom of chamber B by a sleeve e² and a spider e³, interposed between the nut e' and the upper tube-head, the spider e³ affording free communication between said chamber and the tube D. The pipe E thus serves to bind the upper and lower heads together, and thereby counteracts the tendency of the steam to lift the upper 70 head and loosen the joints between the tubes 75 C and D and the upper and lower heads, in which they are secured. A branch pipe E', connected by a T-coupling with the pipe E in the lower chamber A, passes horizontally out through the wall of said chamber to the boiler 80 or other apparatus with which the heater is connected.

F is the water inlet or supply pipe, connected with the opposite side of chamber A, preferably near the top. 85

G is a drain-pipe provided with a suitable cock or valve (not shown) leading out of the lower portion of the annular steam space or belt a' for the purpose of removing from time to time the water of condensation and sediment collecting therein. The bottom a of the lower chamber is provided with a hand-hole and cover a⁴ for the purpose of access to the interior of chamber A without removing the bottom a. 90

H is the shell or jacket of the heater, surrounding the upper head and tubes C C, and detachably secured to the base in the usual or any suitable manner. It is held at the upper end at the proper distance from the upper head B by studs or bolts h h, secured in and projecting radially from said head, as 95

shown in Figs. 1 and 2. The annular steam belt or space a' in the base is divided on opposite sides between the inlet and outlet openings a^2 and a^3 by partitions $J J$, and above these partitions the space between the tubes $C C$ and the jacket H is closed by partition-plates $K K$, extending upwardly to a point near the upper head B . The steam entering the inlet-opening a^2 on one side of the heater is thus compelled to pass upwardly and between the tubes before it can escape through the outlet-opening a^3 on the opposite side of the heater.

My improved heater operates as follows: 15 Water entering the upper portion of lower chamber A through pipe F (shown in Fig. 3) passes thence upwardly, as indicated by arrows, through the tubes $C C$ and D into the upper chamber B , and, rising therein to the 20 level of the upper end of pipe E , descends through said pipe and passes out of the heater through the branch E' to the boiler or other apparatus to be supplied. Steam entering the annular belt a' in the base through the 25 inlet-opening a^2 therein expands and fills said belt on that side of the heater, transmitting a portion of its heat to the walls of chamber A , which in turn transmit it to the water contained therein. The steam being prevented 30 by the partitions $J J$ from passing around said belt a' to the outlet-opening a^3 on the opposite side of the heater is compelled to rise in the space between the tubes C and shell H , and, passing upwardly and between said 35 tubes, gives off its heat, which is transmitted through the walls of the tubes to the water contained therein. The partition-plates $K K$ compel the steam as it rises above chamber A to pass upwardly and across the heater between 40 the tubes $C C$ and D before it can escape through the outlet-opening a^3 , and thereby give off the greatest possible amount of heat which it contains to said tubes, to be transmitted thereby to the water passing 45 through them. As the water enters the upper portion of chamber A the flow is checked and any impurities contained therein are allowed to settle to the bottom, from which they may be readily removed through the 50 hand-hole a^4 . The water thus freed from a portion of the impurities contained therein passes from the upper portion of chamber A through tubes $C C$ and D into the bottom of chamber B , where its flow is again retarded and remaining impurities are allowed 55 to settle. From the upper part of chamber B the purer clarified portion of the water which has been heated by its passage through the tubes C and D exposed to the steam is drawn off through the base by the return and outlet pipe $E E'$. While water is passing 60 through the upper and lower chambers and the tubes connecting them the jacket H may be removed without disturbing the exterior 65 connections of the heater, and any leaks in the joints can thus be readily detected and remedied. For the purpose of inspection, re-

pairs, and the removal of sediment, access is readily had to the interior of chambers A and B and to the open ends of tubes $C C$ and D by removing the bottom a of the lower head and the cover b of the upper head. To remove the bottom a it is only necessary to unscrew the nut e on the lower end of pipe E and take out the bolts by which the bottom a is secured to the base. To remove the cover b it is necessary to first remove the shell H and then the bolts by which said cover is attached to the upper head, but in neither case are the steam and water inlet and outlet connections with the base disturbed.

Various changes in the minor details of the device may be made within the spirit and intended scope of my invention.

I claim—

1. In a water heater, the combination of a base having steam and water inlet and outlet connections and a jacket detachably secured to said base independent of all the external steam and water connections of the heater and removable therefrom without disturbing said connections, substantially as and for the purposes set forth.

2. In a water heater, the combination of a hollow base provided with steam inlet and outlet connections, a hollow head, tubes connecting said head with the base, water supply and discharge connections passing through the base and communicating, one with the water chamber therein and the other with the chamber in said hollow head, and a steam jacket surrounding said tubes, independent of all external steam and water connections of the heater, substantially as and for the purposes set forth.

3. In a water heater the combination of upper and lower chambers and tube heads, tubes connecting said heads and chambers and a return pipe passing through and secured on opposite sides of the upper and lower heads, substantially as and for the purposes set forth.

4. In a water heater, the combination of a base having a water chamber and a steam space or belt around it with inlet and outlet connections, an upper head and chamber, tubes connecting said upper head and chamber with the chamber in the base, a jacket surrounding said tubes, and removable independently of all external connections of the heater and partitions in said steam belt and the space above it between the inlet and outlet steam connections, substantially as and for the purposes set forth.

5. In a water heater, the combination of a base having an inner water chamber and a steam space around it, said steam space having inlet and outlet connections on opposite sides and intermediate partitions, an upper tube head and chamber connected by tubes with the water chamber in the base, a supply pipe leading into the chamber in the base and an outlet pipe leading from the upper part of the upper chamber out through the base, and a removable steam jacket surrounding said

tubes independent of all external steam and water inlet and outlet connections of the heater substantially as and for the purposes set forth.

- 5 6. In a water heater, the combination of a base having an inner water chamber provided with a removable bottom and an annular steam belt around said chamber provided on opposite sides with inlet and outlet connections and intermediate partitions, an upper chamber connected by tubes with the chamber in the base and provided with a removable cover, a water supply or inlet pipe leading into the chamber in the base, a water outlet pipe leading from the upper part of the upper chamber through the lower chamber and secured on the upper side of the upper tube head and on the under side of the bottom of the lower chamber and a branch pipe 15 connected with said outlet pipe and leading laterally out through the base of the heater, substantially as and for the purposes set forth.
7. In a water heater, the combination of upper and lower tube heads and chambers, tubes 20 connecting said chambers, an annular steam space or belt around the lower chamber provided on opposite sides with inlet and outlet openings, a steam jacket inclosing the upper chamber and communicating at the base with said annular steam belt, a water inlet or supply pipe leading into the lower chamber and a return outlet pipe leading out of the upper

portion of the upper chamber through a larger tube into the lower chamber and out through the base of the heater, substantially as and for the purposes set forth. 35

8. In a water heater, the combination of the base having a chamber with a removable bottom, and a steam space or belt around said chamber provided on opposite sides with inlet 40 and outlet openings and with intermediate partitions, an upper chamber provided with a removable cover, tubes connecting said chambers, a pipe passing through the central tube and the lower chamber and secured at 45 its ends by nuts on the under side of the base and on the upper side of the upper tube head, a branch pipe connected with said pipe in the lower chamber and leading laterally out through the base, a water inlet or supply pipe 50 leading into the upper part of the chamber in the base, and a steam jacket inclosing said tubes and the upper chamber and detachably secured to the base independently of the steam and water connections therewith, substantially as and for the purposes set forth. 55

In testimony that I claim the foregoing as my own I affix my signature in presence of two witnesses.
